UNITED STATES PATENT OFFICE

2,231,722

INTERNAL COMBUSTION ENGINE

Frank Johnson, Detroit, Mich., assignor to Ford Motor Company, Dearborn, Mich., a corporation of Delaware

Application January 19, 1939, Serial No. 251,724

7 Claims. (Cl. 123—196)

The object of my invention is to provide improvements in the oiling system of an internal-combustion engine.

A more specific object of my invention is to provide improvements in an internal-combustion engine having what are commonly termed hydraulic valve tappets therein. My improvement comprises means whereby the tappets will be normally supplied with filtered oil, the unique feature being that if the oil filter for any reason becomes clogged, an uninterrupted flow of oil from the engine crankcase will be delivered to the tappets. Although the system is designed for lubricating valve tappets, it may readily be adapted to supply clean oil to other equipment on the engine with the added insurance that under all conditions oil will be provided.

With these and other objects in view, my invention consists in the means for accomplishing the above-mentioned objects, as described in my specification, claimed in my claims, and illustrated in the accompanying drawings, in which:

Figure 1 is a diagrammatic view, illustrating the principal elements of my improved system.

Figure 2 is a fragmentary plan view of my improved motor.

Figure 3 is a sectional view, taken on the line 3—3 of Figure 2.

Figure 4 is a sectional view, taken on the line 4—4 of Figure 2.

Figure 5 is a sectional view, taken on the line 5—5 of Figure 4, and

Figure 6 is a sectional view, taken on the line 6—6 of Figure 4.

Figure 7 is a sectional view similar to that illustrated in Figure 4 showing the relief valve boss at the forward end of the engine, and

Figure 8 is a sectional view, taken on the line 8—8 of Figure 7.

Referring to the accompanying drawings, I have used the reference numeral 10 to indicate the cylinder block casting of a twelve-cylinder V-type motor. An oil pan 11 is secured to the underside of the cylinder block 10 and a crankshaft 12 is rotatably mounted in the cylinder block in the conventional manner. A cam shaft 13 is driven through timing gears 32 from the crankshaft 12, and an oil pump drive pinion 14 is formed on the other end of the cam shaft which is in mesh with an idler gear 15 which latter gear meshes with a pump drive gear 16. The gear 16 is secured to the upper end of a pump shaft 17 which shaft extends downwardly through a pump housing 20 into the oil pan 11. Oil pump gears 18 are driven by the shaft 17 so that upon normal rotation of

the engine oil will be drawn from the pan 11 and forced up through a sleeve-shaped chamber 19 which is formed in the pump housing 20 around the shaft 17. A pressure relief valve 21 is provided in the housing 20, which valve is adjusted to remain closed under oil pressures of less than 45 pounds per square inch delivered by the pump. The chamber 19 is connected with a drilled opening 22 which extends upwardly therefrom to the upper portion of the cylinder block where it intersects a horizontal drilled opening 23. The opening 23 is connected with a main oil distributing pipe 24 which extends lengthwise in the V of the cylinder block. Suitable drilled openings 25 extend from the pipe 24 to the crankshaft and cam 15 shaft bearings of the engine so that oil under pressures up to 45 pounds per square inch is delivered to the various bearing surfaces of the engine. In the claims, these bearing surfaces are designated for convenience as primary bearing 20 surfaces.

A pipe 26 is connected with the vertical opening 22 and a tube 27 extends from the pipe 26 to an oil filter 28. A return tube 29 leads from the filter back to the cylinder block where it is connected 25 to a horizontally drilled opening, shown by dotted lines 30 in Figure 2. A restricting orifice 31 is interposed in the tube 29, this orifice having a clear diameter of $\frac{1}{64}$ ". This orifice is so small that only a minor portion of the oil circulated by 30 the pump gears 18 will flow through the oil purifier. The major portion of the oil flows directly from the opening 22 to the main distributing oil pipe 24.

It will be noted from the drawings that hydraulic valve tappets 33 are reciprocally mounted in the conventional manner within the V of the engine. The inner ends of the tappets bear upon the cam shaft 13. Each of these tappets is provided with an oil reservoir 34 therein and a cylinder 35 is fixed in the reservoir 34 within the tappets 33. A piston 36 is reciprocally mounted within each cylinder 35 and a compression spring 37 at all times resiliently urges the piston 36 upwardly against the bottom of engine valves 38. The spring 37 is not sufficiently strong to force the valve off its seat but simply takes up the clearance between the piston and the foot of the valve. The valves are held in place by conventional valve 40 springs 53. A ball-type check valve 39 is inserted in the bottom of the cylinder 35 so that as the piston 36 is raised upwardly, oil will be drawn through the check valve 39 into the space beneath the piston 36. The check valve 39 prevents the 45 50 55

discharge of oil from the cylinder 35 so that when the cam shaft reciprocates the tappets, the valves will likewise be reciprocated.

It will be noted that a groove 40 is formed 5 around the center portion of each tappet 33, and an opening 41 permits oil to flow into the reservoir 34 to keep same filled and replenish the oil which may leak around the piston.

The valve tappets, just described, are generally 10 referred to as hydraulic tappets and no claim is made herein to any novelty in the tappet per se. This invention relates solely to means for supplying oil under all conditions to operate the tappets rather than to the tappet construction.

15 In order to supply oil to all of the tappets I provide a pair of horizontally extending drilled passageways 42 in the cylinder block 10, which passageways extend through the centers of the respective rows of tappet receiving openings.

20 One of the passageways 42 is connected to the opening 30 shown by dotted line so that oil from the filter is supplied directly to one of the passageways. Figure 3 shows that at the rear end of the crankcase a boss 44 is cast on the cylinder 25 block having a chamber 45 formed in its upper end. A port 46 connects the chamber 45 with the main oil pipe 24 and a pair of drilled openings 47 connect the chamber 45 with the passageways 42, respectively. A ball-type pressure relief valve assembly 48 is inserted into the upper end of the port 46, which relief valve is adjusted so as to open at a pressure of 30 pounds per square inch. This pressure is substantially less than that required to open the relief valve 21. A cap 49, is 35 secured over the chamber 45.

It will also be noted that a boss 50, similar in shape to the boss 44, is cast on the cylinder block 10 at the forward end thereof, and that a pressure relief valve 51 is screwed down into this boss.

40 Openings 52 connect the relief valve 51 with the passageways 42. The relief valve 51 is set to open at 20 pounds pressure per square inch. The plunger of the valve 51 has a flatted portion 43 thereon so that a small amount of oil will at all 45 times flow past the valve onto the timing gears 32. When the valve opens, all of the oil discharged therethrough will flow over the timing gears.

From the foregoing, it will be seen that oil is 50 forced by the pump 20 under a maximum of 45 pounds pressure to the main oil pipe 24, the overflow discharging back to the oil pan. At idling speeds the oil pressure is, of course, considerably less. A portion of the oil delivered by the pump 55 is conducted to the oil purifier 28, the amount being regulated by the $\frac{3}{4}$ " orifice 31. Oil from the purifier 28 flows through the tube 29 to the passageways 42, but the pressure in the passageways is limited to a maximum of 20 pounds by 60 the relief valve 48. Consequently, there is a normal pressure differential of 25 pounds between the main oil pipe 24 and the tappet supply passageways 42. The relief valve 48 is adjusted to open at 30 pounds so that the valve will remain 65 closed under these conditions. However, should the purifier 28 become clogged up to the extent that it will not supply oil under at least 10 pounds normal pressure, then the pressure differential between the passageways 42 and main oil pipe 24 70 will be increased to 30 pounds at which time the valve 48 will open to allow oil to flow directly from the pipe 24 to the valve tappets. This condition will continue until the oil purifier has been cleaned, at which time the preferred system of 75 operation will automatically come into play.

An important feature of this construction is that at no time does the oil exceed a maximum of 25 pounds pressure even though the supply is taken directly from the main oil pipe which may be operating under a 45 pound pressure. 5

The principal advantage of this construction is that only filtered oil will be supplied to the tappets because a small particle of grit might very readily bind one of the tappet pistons and prevent the tappet spring from returning the piston 10 outwardly. This would cause a noisy tappet and reduce the valve opening. However, where only filtered oil is provided, failure of the cleaner may cause all of the tappets to fail, thus reducing the valve lift and causing the valve heads to pound 15 against the valve seats instead of being uniformly decelerated to their closed positions.

Only with the above described construction have these two results been obtainable in one engine. 20

Some changes may be made in the arrangement, construction and combination of the various parts of my improved device without departing from the spirit of my invention and it is my intention to cover by my claims such changes as 25 may reasonably be included within the scope thereof.

I claim as my invention:

1. An engine having principal and secondary bearing surfaces therein, said principal bearing 30 surfaces being lubricated by oil directly from the engine oil pump while said secondary bearing surfaces are normally lubricated by cleaner oil comprising, an oil pump driven by said engine, main oil lines conducting oil from said pump 35 under a substantial pressure directly to said principal bearings, an oil purifier associated with said engine and connected to said main oil line so that oil from said pump is forced through said purifier, a passageway conducting the clean oil 40 from said purifier to said secondary bearing surfaces, a port disposed between said main oil line and said passageway, and a valve disposed in said port which normally remains closed and which upon the stoppage of oil from said purifier while 45 the engine is running, opens to supply oil to said secondary bearing surfaces directly from said main oil line.

2. An engine having principal and secondary bearing surfaces therein, said principal bearing 50 surfaces being lubricated by oil directly from the pump of said engine while said secondary bearing surfaces are normally lubricated by cleaner oil, comprising, an oil pump driven by said engine, said pump having a pressure relief valve associated therewith, a main oil line conducting oil under a substantial pressure from said pump to the said principal bearing surfaces, an oil purifier associated with said engine and connected to said main oil line so that oil from said pump 60 is forced through said purifier, a passageway having a restricting orifice therein conducting the clean oil from said purifier to said secondary bearing surfaces, a second relief valve associated with said passageway, said secondary valve 65 being adjusted to maintain the oil in said passageway at a pressure less than that in said main oil line, a port connecting said main oil line and said passageway, and a third relief valve disposed in said port which is adjusted to open at a pressure intermediate of that of said first and second-mentioned relief valves, for the purpose described. 70

3. An engine having hydraulically operated valve tappets therein comprising, an oil pump 75

- driven by said engine, a main oil line conducting oil from said pump to the principal bearings of said engine, an oil purifier associated with said engine and connected to said main oil line so that the oil from said pump is forced through said purifier, supply means for conducting clean oil from said purifier to the valve tappets of said engine, a port between said main oil line and said valve tappet supplying means, and a valve disposed in said port which normally remains closed and which upon the stoppage of oil from said purifier while the engine is running opens to supply oil to said tappets directly from said main oil line.
4. An engine having hydraulically operated valve tappets therein comprising, an oil pump driven by said engine, a main oil line conducting oil under an appreciable pressure from said pump to the principal bearings of said engine, an oil purifier associated with said engine and connected to said main oil line so that oil from said pump is forced through said purifier, supply means conducting the clean oil from said purifier to said valve tappets, a restricting orifice in said supply means, a port extending between said main oil line and said valve tappets, and a relief valve disposed in said port which normally remains closed and which upon the stoppage of oil from said purifier while the engine is running opens to supply oil to said tappets directly from said main oil line.
5. An engine having hydraulically operated valve tappets therein comprising, an oil pump driven by said engine, said pump having a pressure relief valve associated therewith, a main oil line conducting oil under a substantial pressure from said pump to the principal bearings of said engine, an oil purifier associated with said engine, a conduit conducting oil from said main oil line through said purifier, a passageway conducting oil from said purifier to said valve tappets, said passageway having a restricting orifice therein said passageway having a pressure relief valve associated therewith whereby the oil pressure beyond said orifice is maintained at a substantially lower pressure than in said main oil line, a port disposed between said main oil line and said passageway, and a third relief disposed in said port which upon the maintenance of the normal pressure differential between said main oil line and said passageway remains closed and which upon a material increase in said pressure differential
- opens to supply oil to said tappets directly from said main oil line.
6. An engine having hydraulically operated valve tappets therein comprising, an oil pump driven by said engine, said pump having a pressure relief valve associated therewith which is adjusted to open only at a pressure of substantially 45 pounds per square inch, a main oil line conducting oil from said pump to the principal bearings of said engine, an oil purifier associated with said engine, a conduit connecting said main oil line with said purifier, a passageway conducting clean oil from said purifier to said valve tappets said passageway having a restricting orifice therein between said tappets and said purifier, a second relief valve connected to said passageway whereby the pressure upon said tappets is maintained at substantially 20 pounds pressure per square inch, a port disposed between said main oil line and said tappets, and a third relief valve disposed in said port which is adjusted to open at substantially 30 pounds pressure per square inch so that said third valve normally remains closed and upon the reduction of oil pressure in said tappet passageway below 10 pounds pressure per square inch opens to supply oil to said tappets directly from said main oil line.
7. An engine having timing gears and hydraulically operated valve tappets therein comprising, an oil pump driven by said engine, said pump having a pressure relief valve associated therewith, a main oil line conducting oil under a substantial pressure from said pump to the main bearings of said engine, an oil purifier associated with said engine, a pipe conducting oil from said main oil line to said oil purifier, a passageway supplying oil from said purifier to said valve tappets said passageway having a restricting orifice therein adjacent to said purifier, a second mentioned relief valve connected with said passageway, said relief valve being adjusted to open at a pressure materially less than that at which said pump relief valve is adjusted, the discharged oil from said second mentioned relief valve being deposited upon said timing gears to lubricate same, a port disposed between said main oil line and said passageway, and a third relief valve disposed in said port, which last-mentioned valve is adjusted to open at a pressure between that at which the first two-mentioned relief valves are adjusted to open, for the purpose described.

FRANK JOHNSON.
